UNITED STATES PATENT OFFICE.

CHARLES BREN ELLMIRT, OF SAN FRANCISCO, CALIFORNIA.

HYDROCARBON-BURNER.

SPECIFICATION forming part of Letters Patent No. 773,488, dated October 25, 1904.

Application filed December 30, 1903. Serial No. 187,196. (No model.)

To all whom it may concern:

Be it known that I, CHARLES BREN ELLMIRT, a citizen of the United States, residing at San Francisco, in the county of San Francisco and 5 State of California, have invented certain new and useful Improvements in Hydrocarbon-Burners, of which the following is a specification.

My invention relates to improvements in 10 hydrocarbon-burners, the object of my invention being to provide a device of this character which can be used either with refined oils or with distillates in cook stoves or ranges, in heating-stoves, open fires or grates, fur- 15 naces, or hot-water heaters, which shall be perfectly safe in operation, which will burn the oil or distillate without noise, ashes, odor, or objectionable soot and with a steady even heat, which can be readily lighted, which will 20 not clog up from any cause, which can be used in a cook stove or range without drilling holes into the stove or otherwise mutilating the same, and which shall be adjustable for different sizes and varieties of stoves.

25 My invention therefore resides in the novel construction, combination, and arrangement of parts for the above ends hereinafter fully specified, and particularly pointed out in the claims.

30 In the accompanying drawings, Figure 1 is a side elevation of a cook-stove equipped with my improved burner. Fig. 2 is a vertical longitudinal section of the upper portion of the stove, showing the burner therein. Fig. 3 is 35 a perspective view of the burner detached. Fig. 4 is a perspective view of an air-closure used with an upward draft of air to the burner. Fig. 5 is an enlarged front view, showing the manner of adjusting the burner.

40 My improved burner comprises two principal castings, a rectangular base-plate 1 and an air-conduit 2. The base-plate is formed with a peripheral vertical flange 3, this flange being somewhat higher at one end, as shown at 4, 45 and the conduit 2 has a downwardly-extending wall 5, formed at its lower edge with slots 6, through which and through the raised flange 4 are passed bolts 7, securing the burner

to the base-plate. By means of these slots the height of the burner can be adjusted as 50 desired with reference to the base-plate. The main body of the conduit consists of a horizontal portion 8 for the passage of the air, said portion opening downward at its end, as shown at 9. In this conduit is located the oil- 55 pipe 10, which is passed through and supported by a perforated lug 11, depending from the conduit and the end of which pipe is preferably bent downward to discharge the oil. The oil dropping from said pipe falls 60 through the aperture 9, through which the air passes, onto a circular vaporizing-plate 12, supported by upstanding lugs 13, cast upon the base-plate. Around said aperture 9 the conduit flares, as shown at 14, to a diameter 65 substantially equal to that of the vaporizing-plate, thereby causing the flames to spread around the conduit.

It will be observed that the oil-pipe is supported close to the top of the air-conduit. 70 The advantage of this construction is that thereby the oil is maintained as cool as possible in said pipe. The principal difficulty in constructing an oil-burner for burning California oil is the tendency of the oil to leave 75 deposits in the pipe, which deposits sooner or later clog up the pipe. This deposition takes place more readily the more the oil is heated in the pipe. It is therefore of great importance to keep the oil cool up to the point 80 that it is discharged. The above construction enables this to be done.

In use with a cook-stove the usual grate is removed and is replaced by a metallic plate 15, which is made air-tight by fire-clay or 85 other suitable means, and the burner is laid thereon. The oil-pipe leads upward to the conduit through a small hole in the plate 16, passing into the stove through the hole 17, usually found for fitting the grate into the 90 stove. A valve 18 outside the stove controls the supply of oil.

The conduit 2 has a lip or shelf 19 extending forward from its top as far as the door of the stove, (shown at 20.) The spaces between 95 the sides of the conduit and the sides of the

fire-box at the entrance thereto are filled with fire-clay (shown at 21) to substantially cut off the entrance of air into the fire-box except through the conduit. In order to adjust for 5 different sizes of stoves, the lip or shelf 19 is formed with two transverse grooves 22, dividing said lip into three substantially equal sections and rendering it easy to break off one or two of the sections, as may be desired, 10 according to the size of the stove.

In use the valve is opened and a small quantity of oil is permitted to drop upon the vaporizing-plate. A piece of paper or other inflammable material is then lighted and passed 15 into the air-conduit and allowed to drop upon said vaporizing-plate, igniting the oil. The oil then burns around the flange 14, heating the same. The vaporizer quickly becomes sufficiently hot to immediately vaporize any oil 20 falling thereupon, and the perfect combustion of the vapor of the oil is assisted by the heat of the air-supply thereto, which is highly heated by the flames ascending around the air-conduit. I find that it is of the greatest importance to highly heat the air-supply for 25 burning the oil, and my present construction enables this to be done very effectively. The flange 14 at the bottom of the air-conduit spreads the flames through the fire-box. For 30 the purpose of so spreading the flames the vaporizing-plate 12 is also of peculiar construction. On one side it has an annular concave portion and a central convex portion, the reverse on the opposite side. It is reversible, 35 so that either side may be used uppermost. The central portion is not higher than the rim, so that it will be stable in either position. If used in the position shown in Fig. 2, the flames will be more concentrated than if 40 used in the reverse position. In the latter case the flames would be considerably spread. This construction is also useful to conform to the difference in burning heavy distillates or light distillates. The plate is used in the position in Fig. 2 for burning heavy distillates 45 and in the reverse position for burning light distillates. This construction is also of advantage, as it enables the vaporizing-plate to be tilted slightly to deflect the flames in either direction. Thus by insuring the short 50 bar of iron underneath the edge of the burner-plate nearest the stove - door said burner-plate may be raised on that side, directing the flames to the other end of the fire-box. 55 The adjustment of the base-plate with reference to the conduit is also of importance. If the draft is strong, the base-plate should be farther removed from the conduit than if the draft is poor.

60 A valuable feature of my invention is the arrangement by which the end of the pipe 10, from which the oil drops, and a considerable space immediately below said end are visible

through the opening closed by the stove-door. This is important in two ways—it admits of 65 the burner being placed in an ordinary stove without there being any difficulty in starting the fire through the stove-door and it also allows the person in charge of the stove to readily watch and inspect the dropping of the oil 70 to ascertain whether it is dropping too slow or too fast.

In certain cases it may be desired to have the air-draft enter from below instead of from the side, as shown in Fig. 1. In such cases 75 the closure 25 (shown in Fig. 4) is desirable. This is a casting having a central wall 26 and two lateral walls 27 at right angles thereto, the lateral walls fitting against the sides of the burner below the lip or shelf 19 and the central wall fitting against said lip or shelf. When in this position, access of air to the conduit is shut off except at the bottom.

I claim—

1. A hydrocarbon - burner comprising a 85 base, an air-conduit supported thereon having a horizontally - extending portion opening downward, an oil-pipe in said conduit, and a vaporizing-plate onto which said oil drops, said plate being loosely supported on the base, 90 and having on one side an annular concave portion and a central convex portion, and the other side being curved conversely, the central portion being no higher than the rim, substantially as described.

2. A hydrocarbon - burner, comprising a base, a vaporizing-plate supported thereon, an air-conduit having a horizontally-extending portion, an oil-pipe in said air-conduit and supported thereby discharging onto said plate, 100 and means for supporting the conduit and oil-pipe adjustably relatively to said plate, said means comprising a vertical flange on the base, a slotted vertical wall on the conduit, and bolts through said wall and flange, substantially as 105 described.

3. A hydrocarbon - burner comprising a base-plate, a conduit supported thereon having a horizontally-extending portion discharging downward onto said base-plate and having 110 also an upper lip or shelf extending in the opposite direction from said portion, said lip or shelf being cast with transverse grooves, whereby sections of the same may be broken off to adjust the size thereof, substantially as 115 described.

4. A hydrocarbon - burner comprising a base, an air-conduit having a depending lug and a horizontal air-passage opening downward, an oil-pipe passed through and supported by said lug, extending in said horizontal portion and discharging over said downward opening, and a vaporizing-plate onto which the oil drops, substantially as described.

5. A hydrocarbon - burner comprising a 125 base, an air-conduit having a depending lug

and a horizontal air-passage opening downward, an oil-pipe passed through and supported by said lug, extending in said horizontal portion close to the upper wall thereof, and
5 discharging over said downward opening, and a vaporizing-plate onto which the oil drops, substantially as described.

In witness whereof I have hereunto set my hand in the presence of two subscribing witnesses.

C. BREN ELLMIRT.
